Primary Examiner — Keli L Hill*(74) Attorney, Agent, or Firm* — Jafari Law Group, Inc.(57) **CLAIM**

The ornamental design for a post-curing light assembly, as shown and described.

DESCRIPTION

FIG. 1 illustrates an elevated right-side perspective view of a post-curing light assembly;
 FIG. 2 illustrates an elevated left-side perspective view thereof;
 FIG. 3 illustrates an elevated left-side elevated posterior perspective view thereof;
 FIG. 4 illustrates an elevated right-side elevated posterior perspective view thereof;
 FIG. 5 illustrates a bottom left-side perspective view thereof;
 FIG. 6 illustrates a bottom right-side perspective view thereof;
 FIG. 7 illustrates a right-side view thereof;
 FIG. 8 illustrates a left-side view thereof;
 FIG. 9 illustrates a top view thereof;
 FIG. 10 illustrates a bottom view thereof;
 FIG. 11 illustrates a front view thereof; and,
 FIG. 12 illustrates a posterior view thereof.

(Continued)

The broken lines shown represent unclaimed subject matter and form no part of the claimed design.
